UNITED STATES PATENT OFFICE.

FRANCIS J. TORRANCE, OF ALLEGHENY, PENNSYLVANIA.

DESIGN FOR A LATRINE.

SPECIFICATION forming part of Design No. 23,856, dated December 4, 1894.

Application filed September 12, 1893. Serial No. 485,364. Term of patent 14 years.

To all whom it may concern:

Be it known that I, FRANCIS J. TORRANCE, a citizen of the United States, residing at Allegheny, in the county of Allegheny and State of Pennsylvania, have invented a certain new and original Design for Latrines; and I do hereby declare the following to be a full, clear, and exact description of the invention, such as will enable others skilled in the art to which it appertains to make and use the same.

My invention relates to a design for latrine joints and the design constituting my invention consists in the ornamental configuration of the latrine joint or section as illustrated in the accompanying drawings in which the latrine joint is shown in elevation in Figure 1, and in cross section in Fig. 2.

The leading features of my design consist in the ornamental configuration of the latrine joint which is, as shown in the drawings substantially ovato-deltoid or triangularly egg-shaped in cross section and the vertical or upright flanged bosses surmounting the body of the latrine.

What I claim is—

The design for a latrine joint substantially as described and as shown in the accompanying drawings.

In testimony whereof I have affixed my signature in presence of two witnesses.

FRANCIS J. TORRANCE.

Witnesses:

O. F. GRANT,
WM. K. GRAY.
